UNITED STATES PATENT OFFICE.

KNOWLTON P. DRYSDALE, OF PEORIA, ILLINOIS, ASSIGNOR OF ONE-HALF
TO MARTIN REHFUSS, JR., OF SAME PLACE.

CHECKING AND UNCHECKING DEVICE.

SPECIFICATION forming part of Letters Patent No. 426,250, dated April 22, 1890.

Application filed December 31, 1889. Serial No. 335,526. (No model.)

To all whom it may concern:

Be it known that I, KNOWLTON P. DRYSDALE, a citizen of the United States, residing at Peoria, in the county of Peoria and State 5 of Illinois, have invented a new and useful Improvement in Checkrein Attachments for Harness, of which the following is a specification.

My invention has for its object the provision of an attachment for harness of improved construction for use in securing the checkrein to the harness-saddle, which, while affording ample security against the accidental detachment of the checkrein from the saddle, will offer more readily operative means 10 for fastening and unfastening the checkrein than have been afforded by other means hitherto commonly employed; and my object is, furthermore, to provide such an attachment which may be readily manipulated from 15 the position of the driver.

To the above ends my invention consists in the general construction of the attachment and also in details of construction and combinations of parts hereinafter set forth and 20 claimed.

In the drawings, Figure 1 shows my improvements upon the harness of a horse; Figs. 2, 3, and 4, enlarged broken perspective views illustrating the various features of my improvements in detail, and Fig. 5 a detail view 25 in elevation.

The attachment proper comprises a catch A, rigidly secured to the harness-saddle B, and a link A', provided at one end with an eye t or other means for securing it to the checkrein, and at its opposite end with a stop, preferably in the form of a knob s. The catch A projects upward from the harness-saddle, and may be either in the form of a loop having its upper portion r wider than the lower portion r', as shown, or it may comprise two upwardly-projecting bars bent, preferably, to diverge toward the top in the same manner as the two sides of the loop shown. 35 The body portion p of the link may be either a stiff bar, as shown, or it may be flexible—for instance, in the form of a chain. The knob s is capable of passing readily through the upper part r of the catch, but is too large 40 to pass through it below the upper part, so

that when inserted through the upper part and allowed to drop its withdrawal is prevented by the sides of the catch. The catch is bent, as shown, to incline backward toward the top to prevent the link A' from rising in 55 the catch without drawing upon the checkrein.

In the use of the attachment to check the horse the knob of the link A' is passed through the upper part of the catch and caused to 60 drop to the lower part of the latter, when the strain naturally exerted by the horse upon the checkrein and the weight of the knob will operate to keep the latter down and therefore 65 secure against withdrawal.

In order that the driver may check or uncheck the horse without leaving his position when driving, I provide a line or cord D, fastened at one end to the knob s, and which may be held toward its other end with the reins 70 X in the hand of the driver. The cord D may extend along one of the reins through a guide, or pass through a series of guide-eyes g, placed at intervals along one of the reins to 75 keep it out of the way and render it more 80 easy to be grasped with the reins. While it is generally more desirable that the line D should extend along one of the reins to the hand of the driver to be within easy reach of the latter, the line may be caused to extend 85 along the back of the animal toward the rear end of the harness and fastened to the crupper or turn-back y, as indicated by dotted lines in Fig. 1. The latter way of disposing the line may be preferred where it would bring the line within reach of the driver.

Upon the link and adjacent to the eye t is a stop t', which extends from opposite sides of the link. As the link is drawn through the catch, the stop t' slides up the forward 90 side of the catch, and thus causes the bar to rise coincident with the upper part r of the latter. Therefore to uncheck the horse it is only necessary to draw upon the cord and hold it yieldingly, when the forward strain 95 exerted by the horse upon the checkrein will draw the knob through the upper part of the catch. To check the horse again, the knob is drawn back through the catch by means of the cord and allowed to drop, as before de- 100

scribed, the enlarged part of the link A' affording the eye t, and the stop t' adjacent to the eye operating to prevent the link from being drawn inadvertently entirely through the catch.

What I claim as new, and desire to secure by Letters Patent, is—

In a checkrein attachment for harness, the combination of an upwardly-extending catch 10 A upon the saddle, a link A', an eye t at one

end of the link, through which the checkrein extends and affording a stop, a stop t' upon the link extending each side of the eye, and a stop s at the opposite end of the link to engage with the catch, substantially as described.

KNOWLTON P. DRYSDALE.
